UNITED STATES PATENT OFFICE

168,536

MOBILE MACHINE SHOP TRAILER

Kibbey W. Couse, Newark, N. J.

Application March 7, 1952, Serial No. 18,823

Term of patent 14 years

(Cl. D14—3)

To all whom it may concern:

Be it known that I, Kibbey W. Couse, a citizen of the United States of America and a resident of Newark, in the county of Essex and State of New Jersey, have invented a new, original, and ornamental Design for a Mobile Machine Shop Trailer, of which the following is a specification, reference being had to the accompanying drawing forming a part thereof.

Figure 1 is a side elevational view of the mobile machine shop trailer showing my new design;

Figure 2 is a top plan view thereof;

Figure 3 is an elevational view of the side of the mobile machine shop trailer opposite that illustrated in Figure 1;

Figure 4 is a front elevational view of the mobile machine shop trailer as illustrated in Figure 1;

Figure 5 is a rear elevational view thereof;

Figure 6 is a side elevational view of a mobile machine shop trailer showing portions in open position and other positions in unfolded or extended position;

Figure 7 is a top plan view thereof;

Figure 8 is a side elevational view of the side

of the mobile machine shop trailer opposite that illustrated in Figure 6;

Figure 9 is a front elevational view of the mobile machine shop trailer as illustrated in Figure 6; and

Figure 10 is a rear elevational view thereof.

I claim:

The ornamental design for a mobile machine shop trailer, as shown.

KIBBEY W. COUSE.
